UNITED STATES PATENT OFFICE.

MORTIMER F. BATES, OF BROOKLYN, NEW YORK, ASSIGNOR TO THE SPERRY GYROSCOPE COMPANY, OF BROOKLYN, NEW YORK, A CORPORATION OF NEW YORK.

SELF-DAMPING GYROPENDULUM.

Application filed October 21, 1922. Serial No. 596,008.

To all whom it may concern:

Be it known that I, MORTIMER F. BATES, a citizen of the United States of America, residing at Brooklyn, in the county of Kings 5 and State of New York, have invented certain new and useful Improvements in Self-Damping Gyropendulums, of which the following is a specification.

This invention relates to gyroscopic pendulums and has for its object the provision 10 of an improved device of this character. More specifically it relates to an improved form of damping means for said pendulums.

One of the principal objects of the present invention is to provide means carried 15 by the gyro-frame or housing for damping or suppressing the oscillations of the gyro-pendulum without causing unequal pendulosity of the latter about different axes, said 20 means comprising a universally suspended pendulum whereby it may swing in all directions and directly control the damping forces or torques.

The present invention is in the nature of 25 an improvement of the self-damping gyro-pendulum, shown in Patent 1,324,482 to Morris M. Titterington, dated December 9, 1919, assigned to the assignee of the present invention. Therein, a pendulum was pivotally supported on an oscillatory shaft to swing in a plane at right angles thereto, said shaft carrying a plurality of blades adapted to cooperate with orifices through which air was forced by a fan on the gyro-rotor. 30 When uncovered by the blades, the air forced through the orifices produces a torque about the horizontal axis, thereby tending to quickly suppress all oscillations. Since the mean position of the pendulum must be 35 vertical and as the gyro does not respond instantly to the action of the air jets, the result is that the gyro axis settles on the vertical corresponding to the mean position of the pendulum. By this arrangement, but 40 two jets are employed which act in one plane only. While the present invention is based upon a similar principle of operation, I have greatly simplified the construction, by 45 eliminating parts, and have produced a more rugged and efficient device. In addition, by 50 a novel construction of the pendulum and jets, I am able to obtain an immediate restoring force, no matter in what direction the acceleration forces act, thus not only accelerating the damping action, but tending

to annul the disturbing effect of an acceleration force as soon as the force acts. I employ a hemi-spherical bowl for collecting the air under pressure, which bowl is designed to hold a predetermined volume. A suitable number of nozzles, which may be any number greater than two (three being shown herein) are equi-distantly and tangentially arranged on the outside of the bowl to exert a torque in the proper direction, whereby 60 the gyro may be more readily affected by the action of the air ejected through the nozzles. The nozzles are directly controlled by the pendulum, which has a bob in the form of a part of the sphere, less than a hemi-sphere, universally pivoted at a point representing the center of a sphere of which the bowl is a hemisphere. The orifices to said nozzles are arranged with respect to the pendulum bob so that they will be equally 70 covered when the vertical axes of the pendulum and the gyroscope coincide.

Other novel features of my invention reside in the construction and arrangement of parts.

My invention will be better understood from the following description taken in connection with the accompanying drawings, and its scope will be pointed out in the appended claims.

In the drawings, illustrating what I now consider a preferred form of my invention,

Fig. 1 is a vertical section of a gyro-pendulum taken on two radii represented by the line 1-1 of Fig. 4, to illustrate the structural details and avoid a multiplicity of drawings.

Fig. 2 is a perspective view of the lower portion of Fig. 1 illustrating the air bowl and external jets,

Fig. 3 is an enlarged fragmentary detail of Fig. 1 showing the arrangement of the fan blades, and

Fig. 4 is a sectional view taken on the line 4-4 of Fig. 2 as seen from the bottom illustrating one arrangement the air jets may assume.

Referring now to the drawings in which the numeral 1 indicates the gyro-frame in which is rotatably mounted a normally vertical spindle 2, having suitable bearings at 3 and 4. A gyroscopic rotor 5 is fixed on the spindle 2. This rotor is preferably propelled by a motor of which the primary 6 is secured to the frame 1 and of which the

secondary 7 is carried by said rotor as shown in Fig. 1. Current may be supplied to the stator 6 in any suitable manner. The frame 1 is universally mounted about horizontal axes in the usual manner, which may be accomplished by providing the frame with horizontal pivots, of which one is shown at 8 in Fig. 1, rotatably mounted preferably by means of ball or other anti-friction bearings 9, in a gimbal ring 10, which in turn is similarly mounted for oscillation or rotation about a horizontal pivot at right angles to the pivots 8, as indicated by the dotted circle 11, which pivots are supported by a pair of standards 12, secured to a base 14. But one of the standards 12 is visible in Fig. 1, the same being shown partly in full lines and the remainder indicated by the dotted lines 12'. Preferably, the gyro-pendulum 20 as a whole has its center of gravity only slightly below said axes so that it has a long natural period, say 5 minutes or more. A vertical pin 15 is fixed to the frame 1 in any suitable manner, in axial alignment with spindle 2. Said pin 15 may be provided with a pointer for indicating the angle the base 14 may make with the vertical, or as shown in Fig. 1, it may be connected to a bail 16 for transmitting motion to an indicator in a well known manner. The bail 16 is suitably pivoted in standards 17, located at right angles to the standards 12, and is provided with a suitable race 18 in which the pin 15 may travel. The pin 15 is preferably provided with a roller 19 to minimize the friction in the race 18. A suitable nut 20 may be provided on the pin 15 for the purpose of adjusting the pendulosity.

By making the entire structure carried by the pivots 8 slightly pendulous, it is obvious that the spindle 2 will maintain a substantially vertical position in spite of acceleration forces, provided the gyro-pendulum is properly damped. I therefore provide damping means carried wholly by the frame 1 and constructed substantially as follows:

Air pressure is employed as a source of energy, created by a suitable fan 21 secured to the rotor 5, and by providing the housing 1 with suitable inlet passages 22 and exhaust passages 23. Preferably, the exhaust ports are at right angles to the gyro axis and are above or below (preferably below) the main axes of support 8 and 11 of the gyro-pendulum. As shown in Fig. 3, the fan 21 is provided with a number of blades 24, tangentially arranged with respect to a small circle described about its center, which extend to the periphery of the fan 21 in a direction opposite to the direction of rotation indicated by the arrow, whereby air drawn in at the central portion of the fan will be forced out between the blades 24 to its periphery. As shown in Fig. 1, the fan 21 is dish shaped, with a flat

central portion 21', from which the blades 24 extend, and is secured to the rotor 5 by screws 25. The housing 1 is formed with a member 26, concentric with fan 21, having a curved inner surface, as shown at 26', to leave a suitable clearance between it and the fan, whereby the air from the fan will be directed downwardly. The member 26 is also provided with a suitable number of hollow spokes 27, preferably four, of which one is visible in Fig. 1, which forms the inlet passages 22. The passages 22 communicate with a passage 28, formed by a flange 29 of a hub 30, which hub as shown, also supports the bearings 4. The passage 28 faces the portion 21' of fan 21, so that air may be sucked through the passages 22 to the surface 21' and expelled by the rotation of the blades 24 against the surface 26'. The lower portion of the housing is enclosed by a hemispherical bowl 30 which may be secured to the member 26 in any suitable manner, such as by screws 31, of which but one is shown. A suitable number of exhaust ports 23, preferably three, although a greater number may be employed, are arranged in the same horizontal plane. Said slots are preferably in the form of horizontal slots equally spaced about the circumferences of chamber 30. These ports are best illustrated in Fig. 4, from which it will be seen that these ports are tangentially arranged on the outside of said bowl, each port being provided at its end with a small nozzle 32 to increase the velocity of the air passing from the bowl 30. The exhaust ports 23 are controlled by a pendulum 33. This pendulum may be in the form of a hollow sphere cut on a line parallel to its diameter, which diameter is slightly smaller than the inside diameter of the hemispherical bowl 30, and is supported by an arm 34 so that it will just clear the inside wall of the bowl 30. The arm 34 is threaded at one end to engage threads formed in a central lug 35 formed on the bob 33. At its opposite end, the arm 34 may be formed with a ball 36, or otherwise secured to such a ball, which ball rests in a hemispherical depression formed on a threaded member 37, secured into the hub 30. The lower surface of the member 37 has been conically cut away so that the pendulum 33 may freely swing in all directions. Said pendulum naturally has a very much shorter period than the gyro pendulum, as its length is comparatively short. It will be observed that the ball 36 is supported in the spherical center of the bowl 30, which center is in the same vertical plane as the gyro axis 2. From Fig. 1, it will also be observed that the pendulum 33 is designed to equally close the ports 23, when in its normal position, that position being vertical, or with the axis of the spindle 2 and

arm 34 in the same vertical plane. In such position, all ports are preferably part way open. The spherical surface of the pendulum 33 is formed with a number of 5 concentric grooves 38, which construction is generally known as labyrinth packing to steady the oscillations of the pendulum. To prevent cushioning, and the consequential raising of the pendulum from its suspended 10 seat, an opening 39 is provided in the bottom of the bowl 30, as shown.

In view of the foregoing detailed statement, the operation of my invention will be readily understood from a brief description.

15 Assuming the parts to be in the position shown in Fig. 1, and the rotor 5 rotating clockwise when viewed from the top, air is drawn through ports 22 to passage 28 and by the action of blades 24 driven to the walls 20 26' and directed thereby downwardly into bowl 30. Since the ports 23 are only partially closed by the pendulum 33, but part of the air may escape, as the size of said ports and of said bowl are designed in 25 proper relations to permit the building up of a predetermined pressure within the bowl. Assuming that the motion of the base 14 is such as to cause the gyro to become inclined about the axis 11, moving the pin 15 to the 30 right. Since the pendulum 33 maintains a mean vertical position and is of short period, the port 23 shown at the left in Fig. 1 will be uncovered and the others covered. The jet 32 on this port is open towards the 35 observer when viewed in Fig. 1. The reaction of the air through this jet will create a torque directed from the observer, which will exert a couple about axis 8 at right angles to the axis of inclination and the 40 proper direction to restore the axis 2 in the same vertical with the pendulum axis 34, in accordance with well known laws relating to gyroscopes. The pendulum 33 being universally suspended, it may act on all of the 45 ports 23 in a similar manner in any position the gyro frame 1 may assume. In case the gyro frame should precess through a wide angle, in which event, the pendulum 33 would strike the spokes 27, suitable cushioning means may be provided such as a plurality of rubber stops 40, which may be screwed to the inner upper edge of the bowl 30 as shown in Fig. 1, or a rubber ring may be provided. In this manner, the gyro axis 2 50 is caused to settle on the vertical corresponding to the mean position of the pendulum.

The behavior of my apparatus is also interesting when acted on by an acceleration force. No matter in what direction the acceleration force is exerted, the following 60 effects will be produced;

First, the short period pendulum 35 will be given an inclination in the direction of the applied force,

65 Second, precession of the gyroscope as a

whole will be set up at right angles to the applied force under the well known gyroscopic laws. As soon however, as the pendulum 33 is displaced from its vertical position, a reaction from the air jets occurs 70 as above explained, the net resultant of which is in a plane substantially at right angles to the displacement of the pendulum. Consequently, it will be found that a reaction will be set up which directly opposes 75 the precessional movement of the gyroscope, thus tending to prevent a disturbance thereof by acceleration forces, as well as to quickly damp out any oscillation of the 80 pendulum that may exist.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the 85 combination and relations described, some of these may be altered and others omitted without interfering with the more general results outlined, and the invention extends 90 to such use.

Having herein described my invention what I claim and desire to secure by Letters Patent is:

1. In combination, a gyroscopic rotor, a 100 housing mounted for oscillation about a horizontal axis, rotatably supporting said rotor, and having a plurality of horizontally directed orifices carried by said frame located to one side of said axis, means for causing a flow of gas through said orifices and a 105 pendulum universally suspended in said housing for controlling the orifices.

2. In combination, a gyroscopic rotor, a 110 housing mounted for oscillation rotatably supporting said rotor, a hemi-spherical chamber on said housing having a plurality of orifices tangentially arranged on the outside of said chamber communicating with the interior thereof, means for creating a difference in pressure within said chamber and a 115 pendulum for controlling the orifices.

3. In combination, a gyroscopic rotor, a 120 housing mounted for oscillation rotatably supporting said rotor, a hemi-spherical chamber on said housing positioned with its open end upwards and its spherical center on the rotor spinning axis, and having a plurality of openings communicating with said chamber, and a pendulum having a spherical surface universally suspended at 125 the spherical center of said chamber for covering and uncovering said openings.

4. In combination, a gyroscopic rotor, a 130 housing mounted for oscillation rotatably supporting said rotor, a hemi-spherical

chamber on said housing, means whereby a difference in air pressure within and without said chamber is created, a plurality of horizontal nozzles tangentially arranged on the outside of said chamber communicating with the interior thereof, a pendulum within said chamber for controlling the nozzles, and means universally suspending said pendulum on the gyro spinning axis.

5. In combination, a gyroscopic rotor, a universally mounted frame for rotatably supporting said rotor, a pendulum universally suspended on said frame on the gyro spinning axis, and means controlled by said pendulum and carried by said frame for exerting torques on the latter about a plurality of axes dependent upon the direction of displacement of the pendulum.

6. In combination, a gyroscopic rotor, a housing mounted for oscillation rotatably supporting said rotor, a hemispherical chamber on said housing having its spherical center on the gyro spinning axis, and having a plurality of openings communicating with said chamber, means for creating a differential air pressure within and without said chamber, and a pendulum for controlling said openings universally suspended at said spherical center arranged to equally close the openings when the gyro spinning axis and said pendulum are in a vertical position.

7. In combination, a gyroscopic pendulum, means for damping oscillations thereof comprising a second pendulum having a spherical bob connected to said first pendulum, a hemispherical chamber for said second pendulum having a plurality of slotted openings at right angles to the gyro axis, said openings being controlled by said second pendulum, and means for causing a flow of air through said openings.

8. In a gyroscopic pendulum, means for damping oscillations thereof comprising an inclosing casing having intake passages, a hemispherical chamber having exhaust ports, means carried by the gyroscopic rotor for supplying gas from said intake passages to said chamber, and a pendulum having a bob formed with a spherical surface universally suspended on the axis of said rotor within said chamber, said pendulum being arranged to control said exhaust ports.

9. In a gyroscopic pendulum, means for damping oscillations thereof comprising an inclosing casing having intake passages, a substantially hemispherical chamber having slotted exhaust ports equally spaced around said chamber with their main dimensions lying in the same horizontal plane, means for supplying air from said intake passage to said ports and a pendulum universally suspended on the gyro axis within said chamber for controlling the passage of gas through said ports.

10. In a gyroscopic pendulum, means for

damping oscillations thereof comprising an inclosing casing including a hemispherical chamber, exhaust nozzles tangentially arranged on said chamber located in the same horizontal plane, said chamber having horizontally arranged, spaced slots in said chamber communicating with said nozzles, means carried by the gyroscopic rotor for causing a flow of air through said slots, and a pendulum suspended on the axis of said rotor within said chamber having a bob arranged to cover and uncover said slots.

11. In a gyroscopic pendulum, means for damping oscillations thereof comprising an inclosing casing having an intake passage, a hemi-spherical chamber having exhaust ports, means carried by the gyroscopic rotor for supplying gas from said intake passages to said chamber under pressure, and a simple pendulum suspended on the axis of said rotor within said chamber, having a bob formed with a spherical surface cut from a sphere of slightly smaller diameter than that of said chamber, for controlling the orifices of said exhaust jets, said jets being located on a horizontal plane so as to be equally closed by said bob when the simple pendulum and the axis of said rotor are vertical.

12. In a gyroscopic pendulum, means for damping oscillations thereof comprising an inclosing casing having intake passages, a hemi-spherical chamber having exhaust ports, means carried by the gyroscopic rotor for supplying gas from said intake passages to said chamber, and a pendulum suspended on the axis of said rotor within said chamber, having a bob formed with a spherical surface cut from a sphere of slightly smaller diameter than that of said chamber, for controlling the orifices of said exhaust jets, said bob being provided with a plurality of grooves to form a labyrinth packing between it and said chamber.

13. In a gyroscopic pendulum, the combination with a universally mounted gyroscope, a pendulum universally supported thereon, and means brought into action by the relative displacement of the pendulum and gyroscope in any direction for exerting a torque on the gyroscope at an angle to the displacement of the pendulum.

14. In a gyroscopic pendulum, the combination with a universally mounted gyroscope, a pendulum universally supported thereon, and means brought into action by the relative displacement of the pendulum and gyroscope in any direction for exerting a torque on the gyroscope about a horizontal axis substantially at right angles to the displacement of the pendulum.

15. In a gyroscopic pendulum, the combination with a gyroscope, means for supporting the same for oscillation about a plurality of axes, means for exerting torques on said gyroscope about each of its axes of

support, and a pendulum controller for said means.

16. In a gyroscopic pendulum, the combination with a gyroscope, means for supporting the same for oscillation about a plurality of normally horizontal axes, a plurality of horizontally directed circumferentially spaced air jets secured to said gyroscope to one side of said axes of support,

means for blowing air through said jets, and 10 a universally supported pendulum mounted adjacent said jets for varying the flow of air through the jets in accordance with the inclination thereof.

In testimony whereof I have affixed my 15 signature.

MORTIMER F. BATES.
